SEAM PRESSING MACHINE

Filed July 30, 1930

UNITED STATES PATENT OFFICE

WALTER P. OSGOOD, OF MELDEN, MASSACHUSETTS, ASSIGNOR TO BOSTON MACHINE WORKS COMPANY, OF LYNN, MASSACHUSETTS, A CORPORATION OF MASSACHUSETTS

SEAM PRESSING MACHINE

Application filed July 30, 1930. Serial No. 471,666.

The present invention relates to seam pressing machines which are used in the manufacture of component shoe upper parts to press the connective seams thereof.

5 In certain types of shoes the lining is provided with a friction surface insert which engages the back face of the wearer's heel and holds it from sliding vertically during the act of walking. Usually the insert is located between the rear ends of a pair of quarter lining sections and is secured thereto by at least one seam forming a ridge tending to cause the wearer discomfort.

10 The principal object of the present invention is to produce a seam pressing machine which will press the seams between the lining sections and/or the insert therebetween in an efficient manner.

15 To the accomplishment of this object, and such others as may appear hereinafter, the various features of the invention consist in certain devices, combinations and arrangements of parts, hereinafter described and then set forth broadly and in detail in the appended claims possessing advantages readily apparent to those skilled in the art.

20 The various features of the present invention will be understood readily from an inspection of the accompanying drawing illustrating a generic seam pressing machine and two species thereof, in which,

25 Figure 1 is a view in front elevation of the seam pressing machine;

30 Fig. 2 is a detail view in plan of the anvil jaw or a detail view in underside plan of the pressing jaw;

35 Fig. 3 is a detail sectional elevation on the line 3-3, Fig. 2;

40 Fig. 4 is a detail view in plan of the type of work pressed by the specific anvil and pressing jaw illustrated in Figs. 2 and 3;

45 Fig. 5 is an enlarged detail view in sectional elevation on the line 5-5, Fig. 4, and

50 Fig. 6 is a detail view in plan of a modified form of anvil jaw and the type of work supported thereby for the seam pressing operation.

Referring to Figs. 4 and 5 (which illustrate a piece of work the seams of which have been pressed by the seam pressing ma-

chine embodying the features of one embodiment of the present invention), the quarter sections 7 and 8 of a leather lining are connected by a lap seam 9. Interposed between the rear edges of the sections 7 and 8 is an insert 10 of some leather having a friction surface such, for instance, as a split or suede. This insert engages the back face of the heel of the wearer in the finished shoe and prevents vertical slipping. The rear edge of the section 7 overlaps the insert 10 and is connected thereto by a double line of stitching 11. The rear edge of the section 8 overlaps the insert 10 and is connected thereto by a double line of stitching 12.

55 In order to flatten the seams 9, 11, and 12, and consolidate the parts connected thereby into a unit uniform in thickness throughout its extent as indicated in Fig. 5, the seams 9, 11, and 12 are placed upon a flat surface 13 formed on an anvil jaw 14, Fig. 2. The anvil jaw 14 is mounted, like the anvil jaw disclosed in my Patent No. 1,881,414, October 4, 1932, in the seam pressing machine disclosed therein and indicated generally in Fig. 1 herein.

60 As shown in Fig. 2 the surface 13 is curved in a horizontal plane in accordance with the curvature of the seams 11 and 12. The surface 13 is provided with an extension 15 projecting outwardly therefrom in the median line of the anvil jaw 14 to support the seam 9. Bordering the inside curve of the surface 13 is a blind recess 16, the purpose of which will be explained presently. A blind recess has one open end.

65 The seam pressing machine is provided with a pressing jaw 17 which is secured to an oscillating head 18. The pressing jaw 17 has a curved surface 19 similar to the curved surface 13 on the anvil jaw 14, an extension 20 similar to the extension 15, and a recess 21 similar to the recess 16.

70 As shown in Fig. 1 the seam pressing machine is provided with two anvil jaws 14, two pressing jaws 17, and two oscillating heads 18. The heads 18 are swung forwardly and backwardly by their respective toggle mechanisms, disclosed in the patent hereinbefore identified, automatically and contin-

uously to bring one pair of anvil and pressing jaws into a position of pressure and the other pair of anvil and pressing jaws into a position of clearance. The heads 18 5 are held stationary for an interval when the jaws are brought into their positions of pressure and clearance. During the position of clearance the operative inserts the quarter sections 7, 8, and 10 joined by the seams 9, 10 11, and 12 between the separated jaws and positions the seam 9 on the extension 15 and the seams 11 and 12 on the curved surface 13.

As shown in Fig. 3 the anvil and pressing 15 jaws are heated in the same manner as the corresponding jaws in my patent hereinbefore identified. During the position of pressure the seams are engaged by the surfaces 19 and 20 on the pressing jaw and are flattened thereby under the combined action of heat and heavy pressure so that the parts connected by the seams are consolidated coincidentally into a unit uniform in thickness through its extent.

25 Referring to Fig. 3 the blind recesses 16 and 21 receive the major portion of the insert 10 so that the friction surface thereof may not become glazed by being subjected to the combined action of heat and pressure.

In Fig. 6 the quarter lining sections 22 and 23 are connected, respectively, by the lap seams 24, and 25, to the friction surfaced insert 26. The seams 24 and 25 are positioned, 35 respectively, on the flat faces 27 and 28 of an anvil jaw 29 provided with a recess 30 between the faces 27 and 28. The seams 24 and 25, supported by the anvil jaw 29, are pressed by a pressing jaw having flat faces 40 similar to the faces 27 and 28 on the anvil jaw and a recess therebetween similar to the recess on the anvil jaw. The anvil jaw 29 and its cooperating pressing jaw are heated and are mounted for operation in the seam 45 pressing machine like the jaws 14 and 17 and the corresponding jaws in the patent hereinbefore identified.

It will be apparent to those skilled in the art and with the general objects of the present invention in view that the seams 9, 11, 12, 24, and 25 may be, instead of lap seams, the kind of a seam usually employed as a back seam for shoe quarters such, for instance, as disclosed in Fig. 8 of my Patent 55 No. 1,646,212, October 18, 1927, and that changes may be made in the details of structure, the described and illustrated embodiments thereof being intended as exploitations of their underlying essentials, the features 60 whereof are definitely stated in their true scope in the claims herewith.

What is claimed as new, is:

1. In a seam pressing machine, the combination with means for supporting a pair of 65 shoe quarter sections each connected by an

overlapping seam to an insert, of means for reducing the whole of said overlapping seam to the thickness substantially of one of the shoe quarter sections.

2. In a seam pressing machine, the combination with means for supporting a pair of shoe quarter sections articulated by an overlapping seam curved in a horizontal plane, of means for reducing coincidentally the whole of the curved overlapping seam to 75 the thickness substantially of one of the shoe quarter sections.

3. In a seam pressing machine, the combination with means for supporting a pair of shoe quarter sections each connected by an 80 overlapping seam to an insert and connected by an overlapping seam to each other, of means for reducing the whole of all the overlapping seams to the thickness substantially of one of the shoe quarter sections.

4. In a seam pressing machine for shoe upper parts the combination with an anvil jaw having a flat surface extending in a curve and a recess bounded by the curve, said recess being closed by the curved surface only 90 at one end, of a pressing anvil having a similar surface and recess.

5. In a seam pressing machine for shoe upper parts the combination with an anvil jaw having a flat surface extending in a 95 curve, said surface having an extension projecting outwardly therefrom in the median line of the jaw, and a recess bounded by the curve, of a pressing anvil having a similar surface, extension thereof, and recess.

6. In a seam pressing machine for shoe upper parts the combination with an anvil jaw having a pair of converging flat surfaces and a recess bounded thereby, said recess being open at one end only, of a pressing jaw 105 having a similar recess and a similar pair of converging surfaces.

7. In a seam pressing machine for shoe upper parts the combination with an anvil jaw having a pair of converging flat surfaces and a depressed recess therebetween, said recess being open at one end only, of a pressing jaw having a similar recess and a similar pair of converging surfaces.

In testimony whereof I have signed by 115 name to this specification.

WALTER P. OSGOOD.
